HAROLD B. CHAMBERLAIN, OF EAST ORANGE, NEW JERSEY, ASSIGNOR TO TUZO PRODUCTS CORPORATION, OF NEW YORK, N. Y., A CORPORATION OF NEW YORK

FLOOR CONSTRUCTION

Application filed April 25, 1929. Serial No. 357,916.

This invention relates to flooring and more particularly concerns a flooring construction comprising a plastic material combined with reinforcing and wear-retarding means.

5 Floor surfacing materials of a cementitious composition such as concrete and various other plastic compositions are widely used in railway vehicles, stair-treads, halls and passageways of buildings and similar locations 10 where considerable pedestrian traffic is encountered. Floor surfacing material of this type should be thoroughly reinforced to decrease wear and possibility of rupture thereof at places of greatest traffic and heavy loads, 15 and it is further desirable that such floor surfacings be firmly and permanently secured to the sub-floor structure.

One serious difficulty encountered in connection with floor coverings, particularly in 20 transportation vehicles, arises from the unusual amount of wear and abrasion at the door entrances. Thus at certain points where the pedestrian traffic is extremely concentrated, as at the entrances of vehicles, on stair-treads, etc., depressions are worn into the floor surfacing, requiring repairs or maintenance at such points when the remainder of the floor covering shows no appreciable effects of wear, and since it is desirable to increase the life of the floor covering at these 25 places at least equal to the life of the remainder of the floor covering, the object of this invention is to properly meet these conditions.

30 With the above and other considerations in mind, it is proposed in accordance with the present invention to provide a flooring construction including a plastic floor surfacing provided with improved reinforcing means 35 firmly and permanently secured to the sub-floor, and improved wear-retarding means for effectively delaying abrasion of the floor surface at points of excessive wear. It is a further object of the invention to provide a 40 flooring construction in which the wear-retarding means employed is capable of keying the plastic surfacing material to the floor even after considerable wear has taken place. A further object of the invention comprises a 45 provision of means in the flooring construc- 50

tion for preventing the absorption of liquid from the plastic surfacing material by the sub-floor while the plastic material is being laid and is hardening.

Various other specific objects, advantages 55 and characteristic features of the invention will become apparent as the description thereof progresses.

The composite flooring construction of the present invention preferably includes a sheet 60 of water-resistant material laid directly on the sub-floor and covered by a substantially plane reinforcing member which may conveniently comprise wire mesh of a suitable gauge. A wear-retarding member comprising a perforated metallic plate having raised portions thereof rests upon the reinforcing member, and the wear-retarding member, the reinforcing member and the water-resistant sheet are all firmly and permanently 65 secured to the sub-floor by suitable means. The plastic floor surfacing material is poured over the described construction to the required depth, and flows into locking engagement with the reinforcing member and the 70 wear retarding member. The raised portions of the wear-retarding member are preferably so formed as to lock the plastic material to the sub-floor even after the surface of the plastic material has worn down to such 75 extent that the raised portions of the wear-retarding member are exposed.

In describing the invention in detail, reference will be made to the accompanying drawing, in which:

Figure 1 is a plan view of one embodiment of wear-retarding plate constructed in accordance with the present invention;

Fig. 2 is a sectional view taken along the lines 2-2 of Figure 1;

Fig. 3 is a sectional side view of one embodiment of my improved flooring construction with certain portions thereof broken away to show the details of construction; and

Fig. 4 is a plan view of the construction 95 shown in Fig. 3.

Referring to the drawings, the disclosed embodiment of the wear-retarding member comprises a metallic plate 1 having a plurality of perforations 2 therethrough and 100

provided with a plurality of spaced upwardly protruding circular wear-retarding extensions 3. The extensions 3 and the perforations 2 may be distributed over the surface of the plate 1 in any suitable manner, but a symmetrical distribution of these elements is preferred. Each extension 3 preferably takes the form of a frustated cone, the diameter of the extension being considerably greater adjacent the plane of the plate 1 than at the upper end, as clearly shown in Fig. 2. The curved conical walls of the extension 3 lock the plastic floor surfacing material in place when this material has worn down to the level of the upper edges of these extensions, as hereinafter more fully explained. The extensions 3 are preferably formed integral with the plate 1 and may be conveniently stamped or swaged therefrom, or formed in any other suitable manner. The plate 1 is preferably provided with a plurality of small openings 4 for the reception of fastening means.

Referring now to the composite flooring construction of the invention, one embodiment of which is shown in Figs. 3 and 4, the flooring is preferably laid on a sub-floor 5 of wood, metal or any other suitable material. A sheet 6 of water-resistant or water-proof material such as tar paper is laid directly over the sub-floor 5, and a reinforcing member 7, preferably comprising a continuous layer of wire mesh, is laid above the sheet 6. Suitable means such as nails 8 are employed to secure the wire mesh reinforcing member 7 together with the water-resistant sheet to the sub-floor 5. The wear-retarding plate 1 is laid over the reinforcing member 7 and is suitably permanently secured to the sub-floor 5 by the screws 9 or other suitable means. The floor surfacing substance C in the form of a moist and plastic mixture of cementitious material is poured to the desired depth upon the reinforcing and wear-retarding means as desired, the upper surface thereof being leveled off in any suitable manner at a point above the upper edges of wear-retarding extensions 3. The plastic surfacing material C flows through the openings 2 in the plate 1 and through the wire mesh reinforcing member 7, and when this material sets or hardens, both the plate 1 and the wire mesh 7 are firmly embedded therein, and the floor surface securely keyed or locked to the sub-floor 5.

The moisture-resistant sheet 6 prevents the leakage of moisture from the plastic material C and the absorption of such moisture by the sub-floor 5 before the material has set. Thus the material C is not weakened by the premature extraction of moisture therefrom during the hardening period, and the sub-floor 5 is not rotted by water from the plastic material. The sheet 6 further separates the plastic floor slab C from the sub-

floor 5 and thereby prevents the cracking or rupture of slab upon the warping, sagging or vibration of the sub-floor.

The wire mesh reinforcing member 7 strengthens the entire floor slab and further keys or fastens the surface slab to the sub-floor. The wear-retarding plate 1 also reinforces the plastic material C and keys it to the sub-floor, but the primary function of this plate is to retard the wearing away of the surfacing material C at points such as the entrances or vestibules of vehicles where excessive wear is encountered. When the plastic material C is worn down to such an extent that the upper edges of the extensions 3 are exposed, these extensions retard the further abrasion of the floor surface, and thereby prevent premature failure at points of excessive wear. The tapered or conical shape of the extensions 3 prevents the breakage or dislodgement of the portions 11 of the plastic material C within these extensions 3. When the floor surface is worn down to the edges of the extensions 3, the portions 11 within these extensions are connected to the remainder of the plastic slab by a comparatively thin layer of plastic material below the plate 1 only, but the inclined walls of the extensions 3 firmly key these portions 11 to the remainder of the floor structure and prevent the loosening, cracking or dislodgement thereof.

The wear-retarding plate 1 may be formed of ordinary sheet metal such as iron, brass or aluminum. The rounded shape of the extensions 3 in the plate 1 provides smooth surfaces for contact with the plastic material C, whereby the cracking of the plastic material due to contact with sharp edges is effectively prevented.

Due to the thorough and efficient reinforcing and keying means provided, the flooring construction of the present invention is not only of ample strength to bear considerable loads, but is unusually light in weight. The flooring construction is thus particularly desirable for use in railway vehicles where light strong floors are essential, but the invention is in no way limited to this specific use.

Although the flooring construction of the present invention has been described in connection with a single specific embodiment, it should be understood that various changes, modifications and omissions may be made in the construction without departing from the scope of the invention as defined by the appended claims.

I claim:

1. A floor structure of the type described comprising a sub-floor, a reinforcing member above said sub-floor, a metallic plate above said reinforcing member, upwardly protruding wear-retarding extensions on said plate, means for securing said reinforcing

- member and said plate to said sub-floor and a plastic surfacing material embedding said reinforcing member and said plate and extending above said wear-retarding extensions. 5
2. A floor structure of the type described comprising a sub-floor, a layer of moisture-resistant material on said sub-floor, a network of reinforcing elements above said moisture-resistant material, a metallic plate above said reinforcing elements, upwardly protruding wear-retarding extensions on said plate, means for securing said plate and said reinforcing elements to said sub-floor, and a mass 10 of plastic floor surfacing material embedding said reinforcing member on said plate and extending from said moisture-resistant material to a plane above said wear-retarding extensions. 15
3. A floor structure of the type described comprising a sheet of moisture-resistant material, a network of reinforcing elements above said sheet, a metallic plate above said reinforcing network, a plurality of wear-retarding extensions integral with and extending 20 upwardly from said metallic plate and a plastic surfacing material embedding said reinforcing elements and said plate and extending from said moisture-resistant sheet to a plane above said wear-retarding extensions. 25
4. A floor structure of the type described comprising a sub-floor, a sheet of moisture-resistant material on said sub-floor, a wire mesh reinforcing element above said sheet, 30 means for securing said reinforcing element and said sheet to said sub-floor, a perforate metallic plate above said reinforcing element, a plurality of spaced upwardly protruding wear-retarding extensions on said plate, 35 means for securing said plate to said sub-floor, and a plastic surfacing material embedding said reinforcing member and said plate and extending from said moisture-resistant sheet to a plane above the wear-retarding extensions of said plate. 40
5. A floor structure of the type described comprising a sub-floor, a sheet of moisture-resistant material on said sub-floor, a wire mesh reinforcing element above said sheet, 45 means for securing said reinforcing element and said sheet to said sub-floor, a perforate metallic plate above said reinforcing element, a plurality of hollow frusto-conical wear-retarding extensions protruding upwardly from said plate, means for securing said plate to said sub-floor, and a mass of plastic floor surfacing material surrounding said plate and filling said extensions. 55
6. A floor structure of the type described comprising a sub-floor, a reinforcing element above said sub-floor, a metallic plate above said reinforcing element, a plurality of hollow upwardly protruding wear-retarding extensions of rounded section on said plate, 60 said extensions being open at their upper 65 ends and being of larger section at the plane of said plate than at their upper ends, a mass of plastic floor surfacing material surrounding said plate and said reinforcing elements and filling said hollow extensions, and means for securing said plate to said sub-floor. 70
7. A floor structure of the type described comprising a sub-floor, a sheet of moisture-resistant material on said sub-floor, a wire mesh reinforcing element above said sheet, a perforate metallic plate above said reinforcing element, a plurality of spaced upwardly protruding hollow extensions of rounded section formed integral with said plate, said extensions having an upwardly constricted inner bore and being open at their upper ends, means for securing said plate to said sub-floor and a plastic floor surfacing material surrounding said plate and said reinforcing member and filling said hollow extensions, 75 said surfacing material extending from said moisture-resistant sheet to a plane above the upper ends of said extensions. 80
